United States Patent Office

Des. 187,153
Patented Feb. 2, 1960

187,153

DINNER PLATE OR SIMILAR ARTICLE

Michael J. Szymanski, Camillus, N.Y., assignor to Onondaga Pottery Company, Syracuse, N.Y., a corporation of New York

Application September 4, 1959, Serial No. 57,443

Term of patent 14 years

(Cl. D44—15)

The drawing is a plan view of a plate of conventional configuration showing my new design.

I claim:

The ornamental design for a dinner plate or similar article, as shown and described.
